AUTOMATIC GAIN CONTROL CIRCUIT

Hans Bartels and Hans Friedrich, Berlin, Germany, assignors to Telefunken Gesellschaft für Drahtlose Telegraphie m. b. H., Berlin, Germany, a corporation of Germany

Application May 12, 1934, Serial No. 725,264
In Germany April 12, 1933

5 Claims. (Cl. 179—171)

The present invention is concerned with improvements in automatically regulated amplifier apparatus. It is known that automatically regulated amplifier arrangements are employed for 5 the purpose to reduce the large dynamic power of original programs or productions, in the case of the interposition of electrical transmission systems, to the value which can be transmitted by such transmission systems.

10 In devices serving to insure automatic gain control, as is well known in the art, transmission means are inserted in the amplifier path whose transmission measure is variable as a function of a biasing voltage. However, the variation of 15 the amplification factor or gain, i. e., of a biasing potential, is associated with a change of the static current of the regulator means furnished from a direct current source such as, for instance, an electronic tube or a rectifier. For example, in the case of an electron tube of the kind 20 used for anti-fading or fading compensation purposes, a large plate feed current (static current) corresponds to high gains, and small feed currents to low gains.

25 In order to preclude feedbacks by way of joint sources of current, and to prevent supply-line noises or hums in mains-connected amplifiers, it is necessary in the case of amplifying devices to include filter networks in the plate leads of 30 the tubes. If in a similar way a gain-control apparatus is connected with the same batteries, or with a power pack united with a supply-line, plate filters must be provided also in this case so as to prevent feedbacks and to eliminate disturbing 35 frequencies.

It has also been found that automatic gain control must be effected inside a very brief length of time, in fact, the building-up period should 40 preferably be less than 100 milli-seconds. However, since the building-up times of the filters are considerably greater if sufficient plate smoothing is to be insured (the same ranging around 1 sec. and over), difficulties are encountered in the attempt of combining plate filter networks in 45 connection with automatic gain or volume control schemes. Now, the purpose of this invention is to overcome difficulties in the said direction.

Inasmuch as in normal circuit schemes, as 50 above pointed out, plate filters can not be used, the regulator tubes according to the present invention, may be provided with a distinct D. C. voltage (or separate auxiliary grid voltages). Owing to the low internal resistance of the plate battery, and in the absence of plate filters, the 55 building-up and the decay period and constant of

the regulator system can be made in practice of any desired small value.

Another solution would reside in the use of 5 artificial networks which have the purpose of making conditions so that, in the presence of variations of the feed current of the regulator system, the current derived from the D. C. source will remain constant or practically so.

It is also feasible to employ multi-grid tubes, 10 say tubes with a space-charge grid (or space-charge tubes), in which the stability or constancy of the emission current (i. e., of the plate current plus space-charge current) is used for the purpose of stabilizing the value of the aggregate current from the D. C. source conducted by way 15 of the filter chain, in spite of changes in the plate feed current of this tube. Instead of a space-charge tube, it would also be feasible to use tubes with several auxiliary grids for the purpose of insuring the identical effect.

The novel features which we believe to be 20 characteristic of our invention are set forth in particularity in the appended claims. The invention itself, however, both as to its organization and method of operation, will best be understood by reference to the following description, 25 taken in connection with the drawings, in which we have indicated diagrammatically several circuit organizations whereby our invention may be carried into effect.

In the drawings:—

Fig. 1 shows a push-pull circuit embodying one 30 form of the invention,

Fig. 2 shows a modification of the arrangement 35 in Fig. 1,

Fig. 3 illustrates another embodiment of the 40 invention,

Fig. 4 shows a modified form of the arrangement shown in Fig. 3,

Fig. 5 shows still another embodiment of the 45 invention.

Figure 1 shows a section from the circuit diagram of an ordinary push-pull amplifier, to which the invention has been applied, this figure representing only the part of the automatic arrangement for the control of the amplification. The 50 electrical impulses are supplied from the input side of the transformer 1, connected as mentioned, in push-pull, from where the impulses are passed to the grids of the controlled tubes 2 and 3. The grid bias voltage source 4 may be of any type. The heating circuits for the tubes are omitted from the figure. Furthermore, the impulses are supplied to the transformer 5. The 55 anode potential for the controlled tubes 2 and 3

is taken from a rectifier, not shown, across a filter chain 6. The time constant of this filter chain 6 is of such value that at any variations of the anode current for the purpose of regulating 5 the amplification, the amplification changes occur practically only after a greater length of time.

According to the invention, an ohmic resistor 7 is inserted in the anode circuit, namely between filter chain 6 and controlled tubes 2 and 3; the current received by this resistor is many times the anode current received by the controlled tubes. It has been found advantageous to make the current in the resistor 7 approximately ten times as large as that for the anode circuit of the controlled tubes. Due to this resistor the anode filter chain 6 is damped to such an extent that the desired variation in the anode current of the controlled tubes is made possible within the time 20 value last referred to. The time constant of the filter chain is only of minor importance in view of the small part of the anode current variations as compared with the total current.

Figure 2 shows a circuit, in accordance with 25 Figure 1, whereby the ohmic resistor 7 in Figure 1 is replaced by a glow tube 8. The functioning of this circuit is identical with that of the circuit according to Figure 1.

Figure 3 shows a control circuit for hexodes, 30 in which the hexodes are connected for instance in push-pull. The current impulses from the input side are supplied to the grids 12 and 13 of controlled tubes 10 and 11, across the transformer 9. The grid battery 14 may consist of any type of 35 current source furnishing a negative potential. The heating circuits for the tubes is likewise not shown in particular. The second grids 15 and 16 of the tubes are placed at a positive potential across battery 17. The further grids 18 and 19 40 are connected to the plate current source 20, the latter having also connected thereto the anodes 21 and 22 of tubes 10 and 11, across the push-pull connected primary windings 23 and 24 of output transformer 25. The output circuit is 45 placed at the secondary windings 26 and 27 of the transformer. The grids 28 and 29 of tubes 10 and 11 are connected to the negative voltage source 31, across a resistor 30. Ahead of the input transformer 9 the incoming current impulses 50 are in part branched off through lines 32 and 33 in parallel to said transformer, and they are applied to the resistor 30 through a path including an amplifier 34, rectifier 35 and a time constant unit 36.

In the tube 10 the following occurs, and the 55 same is likewise true for the tube 11. The electrons emitted by the cathode of the tube are influenced at the frequency of the impulses impressed upon the grid 12 by the transformer 9, and they are passed to the grid 15 which, due to 60 its positive potential, acts as an anode. The voltage of this grid acting as an anode, is equal to, or lower than, the potential at anode 21. A portion of the electrons passes through grid 15, 65 this passage being dependent upon the "through-grip" (reciprocal of amplification factor) of grid 15, and furthermore these electrons reach grid 18. While a part of the remaining electrons is deviated by 18, a further part of the electrons 70 reaches the control grid 28, and then the anode 21. The sum of the electrons received by the grid 18 acting as anode, and by the anode 21, is constant, and hence this is also true for the total current flowing in the circuit (battery 17/20 and 75 tube 10), containing the parallel connected grid

18 and anode 21. The current distribution in the current branches placed at grid 18 and anode 21, however, depends upon the voltage condition of grid 28, namely in such manner that when the negative voltage at the control grid 28 decreases, 5 i. e. towards the positive, the current in the branch placed at the anode 21, increases, and the current in the branch at 18 decreases. When the negative potential at the control grid 28 becomes higher, i. e. towards the negative, the reverse 10 takes place.

In the circuit, according to Figure 3, the impulses for the control grids 28 and 29 are derived from a place ahead of the input transformer 9 of the control circuit. In Figure 4 the same control circuit is shown; however, in this case, the impulses for the control grids 28 and 29 are tapped in back of the output transformer 25 preferably behind a further amplifier 37. In the circuit according to Figures 3 and 4 corresponding parts 20 are designated by identical reference characters. The danger of feed back is less in a circuit according to Figure 3 than in the case of the circuit of Figure 4. The mode of control is obviously not solely limited to the push-pull circuit. 25

In the circuit according to Figure 5 a further example for a control arrangement is shown for instance for a simple pentode circuit. In the circuit of Figure 5, the impulses are applied to a pentode across the input transformer 38 and grid 39 of the tube 40. The grid 39 receives a negative potential from the voltage source 41. The grid 42 acting as an anode is placed at voltage source 43, to which there is also connected the anode 44 across the primary winding 45 of the output 35 transformer 46. The output circuit is connected to the secondary winding 47 of transformer 46. The control grid 48 of the control tube 40 is connected to a negative voltage source 49. The variable control voltage is applied to the terminals 50. The connection of the control voltage is carried out in the manner shown in the diagrams of Figure 3 or 4. The control performance is similar to that indicated for Figures 3 and 4. The electrons are influenced at the frequency of 45 the impulses impressed upon grid 39. The proportion of the electrons deviated by grid 42 acting as anode, and by the anode 44, i. e., the currents flowing through the circuits connected to these electrodes, will be influenced by the variation 50 of the control voltage at grid 48, in the manner above described.

While we have indicated and described several 55 systems for carrying our invention into effect, it will be apparent to one skilled in the art that our invention is by no means limited to the particular organizations shown and described, but that many modifications may be made without departing from the scope of our invention, as set forth in the appended claims. 60

What is claimed is:—

1. In combination with a source of electrical waves and a load output circuit, a pair of electron discharge tubes, each of said tubes including a cathode, an input grid, an output anode, a positive grid disposed adjacent said input grid, and a gain control grid disposed between the anode and said positive grid, the input electrodes of said tubes being arranged in push-pull relation, and the output anodes of said tubes being arranged in 65 similar push-pull relation, means for deriving from the electrical waves a direct current voltage whose magnitude is dependent upon the magnitude of said waves, and means for impressing said direct current voltage upon the gain control grids 70

of said tubes in a sense such that the gain of said tubes is inversely related to the amplitude of said waves.

2. In a system as defined in claim 1, each of said tubes including in addition a positive grid disposed between the input grid and the first mentioned positive grid.

3. In a system as defined in claim 1, said means for producing said direct current voltage comprising a network which includes at least a rectifier, a time constant network and an impedance for developing said direct current voltage.

4. In a system as defined in claim 1, said impressing means including a source of fixed direct current voltage for maintaining a normal negative bias on said gain control grids of both tubes in the absence of incoming electrical waves.

5. In combination with at least one tube having a cathode, a positive plate, a normally nega-

tive signal grid adjacent the cathode, a gain control grid adjacent the plate, a positive grid disposed between the signal and gain control grids, said cathode, signal grid, positive grid, gain control grid and plate being arranged in the order named, an audio current source coupled between the cathode and signal grid, an audio output circuit coupled to the plate, a source of direct current voltage having its negative terminal connected to said cathode and its positive terminal connected both to said plate and positive grid, a gain control network comprising an amplifier having its input connected to the said audio source, a rectifier coupled to the amplifier, a time constant circuit connected to the rectifier output, and means for impressing the rectified audio voltage upon the said gain control grid.
